Primary Examiner — Rhea Shields(74) *Attorney, Agent, or Firm* — Fitch, Even, Tabin & Flannery LLP(57) **CLAIM**

I claim the ornamental design for a beverage container, as shown and described.

DESCRIPTION

FIG. 1 is a perspective view of a beverage container showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is top plan view thereof;

FIG. 7 is a bottom plan view thereof; and,

FIG. 8 is an enlarged left side view of the encircled area shown in FIG. 2.

In the drawings, the broken lines are for the purpose of illustrating environment only and form no part of the claimed design.
